UNITED STATES PATENT OFFICE

2,604,565

CIRCUIT BREAKER EMPLOYING A PAIR OF
ARC CHUTESGeorge A. Burnham, Saugus, Mass., assignor to
Allis-Chalmers Manufacturing Company, Milwaukee, Wis., a corporation of Delaware

Application November 10, 1949, Serial No. 126,572

4 Claims. (Cl. 200—148)

1

This invention relates to circuit interrupting devices and more particularly to arc extinguishing means for use in connection therewith.

In the construction and operation of circuit interrupters, it is frequently necessary to provide means for extinguishing quickly the arc which is drawn between separable arcing contacts. This arc is usually blown by blowout means, such as an air blast, into an arc chute which is arranged to quench the arc by lengthening it, cooling it, or otherwise.

The interrupting capacity of a circuit breaker in a high voltage circuit depends to a great extent on the circuit characteristics relating to the rate of increase of recovery voltage when the current is interrupted. Although the breaker may be successful in interrupting the current momentarily, the recovery voltage across the interrupting gap may rapidly rise to such a value that arcing is reestablished before the breaker has sufficiently increased the dielectric strength of the gap. To increase the interrupting capacity of the breaker, it would be necessary to increase the pressure and the intensity of the gas blast. If it is impractical to increase the gas pressure, the size of the blast passage or the type of gas passage or passages may be varied to provide for greater gas volume or greater interrupting ability. Such changes, however, usually result in either a more expensive or larger breaker.

In accordance with the invention claimed a fluid blast circuit interrupter is provided which comprises a pair of arcing contacts mounted within an arc chamber or manifold. The manifold is connected to a source of fluid under pressure and to an arc extinguishing structure. The arc extinguishing structure comprises a first and a second arc chute. The second arc chute cooperates with the arcing contacts to constitute a complete backup or standby breaker, which extinguishes the arc if the first arc chute fails to clear the circuit.

In addition, the chutes are so arranged that if the back pressure developed in the first arc chute renders that arc chute inoperative, the back pressure established will tend to extinguish the arc in the second arc chute, and vice versa. A pair of nozzles may be provided between the manifold and the arc chutes. One of these nozzles may provide a blast of fluid through the first nozzle and into the first arc chute immediately before and during separation of the arcing contacts. After separation of the arcing contacts and the initial blast, the second nozzle may

2

provide a second blast of fluid to flow through the second nozzle and into the second arc chute.

By inserting a suitable resistor in the circuit, the voltage recovery rate of the circuit may be decreased, and if the circuit is not interrupted by the first blast of fluid through the first arc chute, it may be interrupted in the second chute at a greatly decreased current at a much more favorable recovery rate by the second blast of fluid through the second arc chute. In this manner, the interrupting capacity of the circuit breaker for a given blast pressure and gas consumption is greatly increased.

It is, therefore, one object of the present invention to provide a new and improved arc interrupting device.

Another object of the invention is to provide a new and improved arc interrupting device in which an arc chute acts as a standby to extinguish the arc if another arc chute fails to clear the circuit.

A further object of this invention is to provide a new and improved arc extinguishing means which utilizes undesirable back pressure in one arc chute to aid in extinguishing the arc in another arc chute.

A still further object of this invention is to provide an improved fluid blast circuit interrupter in which a blast of fluid under pressure is caused to flow through a first arc chute immediately preceding and during contact separation and a second blast of fluid under pressure is caused to flow through a second arc chute only after contact separation and the initial blast.

A still further object of this invention is to provide an improved fluid blast circuit interrupter in which a plurality of arc chutes and gas blasts extinguish a series of arcs drawn by a single movable arcing contact.

Objects and advantages other than those above set forth will be apparent from the following description when read in connection with the accompanying drawing in which:

Fig. 1 is a diagrammatic showing, partly in cross section, of a fluid blast circuit breaker embodying the present invention;

Fig. 2 is a view in cross section of the embodiment illustrated in Fig. 1 taken along the line II—II; and

Fig. 3 is a view in cross section of the embodiment illustrated in Fig. 1 taken along the line III—III.

The cross blast type air blast circuit breaker shown by way of example in Fig. 1 comprises relatively movable arcing contacts, such as fixed con-

tact structure 7 of the finger type and blade-like contact 8. The fixed contacts structure may comprise a plurality of current carrying contacts and an arcing contact as is well known, and is electrically connected to one line terminal 9 of the breaker. The blade-like movable contact 8 is connected to the other line terminal 10. Although in general, circuit breakers of the type considered in Figs. 1, 2 and 3 are provided with a plurality of similar pole structures, one for each phase of a polyphase electric circuit, only one such pole structure is shown in the drawing and the circuit breaker will be described in detail as if it were of the single pole unit type.

The movable contact 8 is suitably connected to an actuating mechanism (not shown) through a connecting rod 11 for operating the movable contact between closed and open circuit positions.

For the purpose of extinguishing the arcs formed between the contacts when a power circuit connected thereto is opened, an insulating arc extinguishing structure 12 is arranged with respect to the contacts so that the arc is drawn at the entrance of the structure directly opposite a gas blast supply conduit 13. The conduit 13 is suitably connected through a blast valve (not shown) to a source of compressed gas, such as air, comprising for example a storage tank and compressor equipment (not shown).

The arc extinguishing structure 12 may, for example, comprise a first arc chute 14 and a second arc chute 15 mounted adjacent to an arc chute 14. A fixed arcing contact 19 is mounted between arc chutes 14 and 15 at the upstream end thereof. Arc chute 15 is so arranged in relation to arc chute 14 that it acts as a standby or backup for arc chute 14, but functions cooperatively as well. The arc chutes 14 and 15 may be rectangular or circular in form.

An arc chamber or manifold 16 of insulating material is arranged between the gas supply conduit 13 and the arc extinguishing structure 12 for distributing the fluid under pressure from the point where it arrives in highly concentrated form by the supply conduit 13 to the arc chutes 14 and 15. Arcing contacts 7 and 8 are mounted within manifold 16 and the arc drawn upon separation of the contacts is enclosed by the manifold upon inception thereof. Manifold 16 provides a pair of arcing zones 25 and 26 which are located at the upstream end of a pair of nozzles 17 and 18, respectively. Nozzles 17 and 18 direct the fluid under pressure from manifold 16 to arc chutes 14 and 15.

Nozzle 17 may be so arranged that some fluid under pressure may pass therethrough even when movable arcing contact 8 is in the closed position, while nozzle 18 may be arranged similarly to nozzle 17 or may be so arranged that the movable arcing contact 8 effectively seals nozzle 18 until contact 8 has traveled a predetermined distance in contact opening direction.

One end wall of manifold 16, as illustrated in Fig. 1, defines a passage 20 therethrough which accommodates the movable sickle-shaped blade contact 8. This wall closely surrounds contact 8 and controls the escape of compressed air or arc products through passage 20 into the atmosphere. A plurality of transversal grooves 21 provided in the walls of passage 20 tend to establish eddies in the small flow of escaping air and arc products through passage 20 and thus minimize the rate of that flow.

A pair of probe electrodes 22 and 23 may be mounted within arc chutes 14 and 15, respec-

tively, for aiding arc extinguishment. A current limiting resistor 24 may interconnect electrode 22 and the multiple finger contacts of the fixed contact structure 7, thus lowering the value of the arc current during arc extinguishment.

The circuit breaker illustrated in the drawing is shown with the cooperating arcing contacts in the closed circuit position. An opening operation is initiated by admission of air under pressure to supply conduit 13 and manifold 16. As illustrated in Fig. 2, nozzle 17 is open at all times to manifold 16, thus allowing air to flow through arc chute 14 substantially simultaneously with its admission to manifold 16. The flow of air through nozzle 18 and arc chute 15 is at first substantially prevented by contact 8, which occupies the entire entrance portion of nozzle 18 as illustrated in Fig. 3, thus effectively sealing it.

Actuation of the connecting rod 11 moves blade contact 8 toward the right to open the electric circuit. As the blade contact 8 is separated from the fixed contact 7, an arc is drawn across the arcing zone 25 of the first arc chute 14 and substantially concurrently therewith a path is opened for blast of air of high intensity through the supply conduit 13, manifold 16, nozzle 17 to the first arc chute 14. Although contact 8 does not seal nozzle 17 when in its closed position, it may obstruct nozzle 17 sufficiently to prevent a blast of high intensity air from flowing into nozzle 17 and arc chute 14 until after a predetermined movement of the contact. This blast includes all the air being supplied through conduit 13, and drives or loops the arc from zone 25 into arc chute 14. The heat of the arc causes vaporization of metal from the contacts and also causes violent expansion of the air surrounding the arc. The production of the arc thus is accompanied by a virtual explosion, which tends to reverse the air blast in pipe 13 and chamber 16 by its back pressure.

Frequently the arc is interrupted in the first arc chute by the blast of air flowing through nozzle 17, at least if the back pressure does not actually reverse the blast. If the arc is not already extinguished when the tip of the blade moves beyond contact 19, the arc is lengthened and divided into a number of serially connected arcs extending between contacts 7, 19 and 8. The second arc chute 15 and nozzle 18 are uncovered upon a predetermined movement of contact 8 and at least one part of the arc is driven or looped from zone 26 into arc chute 15 by a separate and distinct blast of air from nozzle 18. Thus, a single arc in each arc chute is acted upon by a separate and distinct air blast. Manifold 16 is large enough so that the blasts may be of substantially the same intensity.

In case the explosive or back pressure created in arc chute 14 is great enough to prohibit extinguishing the arc in that particular chute, the second arc chute 15 will cooperate with the contacts to act as a backup breaker to extinguish the arc and clear the electric circuit. Each arc chute has a common contact system and a common source of air under pressure, but each arc chute has sufficient interrupting capacity to interrupt the circuit. In fact, the arc chutes are so arranged that if back pressure in the first arc chute renders that arc chute inoperative, that back pressure will reduce the air flow in that arc chute and therefore make an increased air flow available to extinguish the arc segment in the second arc chute which has a free path to atmosphere. This same operating condition

occurs if the second arc chute is rendered inoperative by back pressure, that back pressure will reduce the air flow in the second arc chute and help to extinguish the arc in the first arc chute. Thus, the efficiency of either arc chute is increased by the back pressure of the other arc chute.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. In a fluid blast circuit interrupter, the combination comprising: a source of fluid under pressure, arcing contacts comprising a stationary contact and a movable contact for establishing an arc, an arc extinguishing structure mounted adjacent said contacts comprising a first arc chute and a second arc chute, a probe electrode mounted within said first arc chute, a resistor for connecting said probe electrode in series with said stationary contact, said first arc chute receiving the arc drawn upon initial separation of said contacts and said second arc chute receiving at least a portion of said arc thereafter if said arc is not extinguished in said first arc chute, and means for providing a first blast of fluid from said source through said first arc chute immediately before and during separation of said contacts and only after separation of said contacts providing a second blast of fluid from said source through said second arc chute.

2. In a fluid blast circuit interrupter, the combination comprising: a source of fluid under pressure, a manifold connected to said source for providing blasts of fluid under pressure, a pair of arcing contacts mounted within said manifold for establishing an arc upon separation thereof comprising a relatively stationary contact and a movable contact, and an arc extinguishing structure mounted adjacent said contacts comprising a first arc chute and a second arc chute both connected to said manifold, a probe electrode mounted within said first arc chute, a resistor for connecting said probe electrode in series with said stationary contact, said first arc chute receiving the arc drawn upon initial separation of said contacts and said second arc chute receiving at least a portion of said arc thereafter if said arc is not extinguished in said first arc chute, said manifold providing a first blast of fluid through said first arc chute immediately before and during separation of said contacts and only after separation of said contacts providing a second blast of fluid through said second arc chute.

3. In a fluid blast circuit interrupter, the combination comprising: a source of fluid under pressure, separable arcing contacts for establish-

ing an arc, a conduit for conveying a blast of fluid from said source adjacent said contacts for extinguishing the arc drawn upon separation of said contacts, an arc extinguishing structure mounted adjacent said contacts comprising a first arc chute and a second arc chute, a probe electrode mounted within said first arc chute, a resistor for connecting said probe electrode in series with one of said arcing contacts, an arc chamber surrounding said contacts connecting said conduit with said arc extinguishing structure for enclosing the arc upon inception thereof, and means comprising a pair of nozzles for directing blasts of fluid from said chamber into said arc chutes, one of said nozzles directing a first blast of fluid through said first arc chute immediately before and during separation of said contacts and the other of said nozzles directing a second blast of fluid through said second arc chute only after separation of said contacts.

4. In a fluid blast circuit interrupter, the combination comprising: a source of fluid under pressure, a manifold connected to said source for providing blasts of fluid under pressure, contact means mounted within said manifold comprising stationary multiple finger contacts and a cooperating movable blade contact for establishing an arc, an arc extinguishing structure mounted adjacent said contacts comprising a first arc chute and a second arc chute, a probe electrode mounted within said first arc chute, a resistor for connecting said probe electrode in series with said multiple finger contacts, said first arc chute provided for extinguishing the arc drawn upon separation of said contacts and said second arc chute provided for extinguishing said arc if it exists after a predetermined movement of said movable contact, and means comprising a pair of nozzles one for each of said arc chutes for directing blasts of fluid from said manifold into said arc chutes, said movable blade contact obstructing the nozzle for said first arc chute to limit the flow of fluid from said source through said first arc chute until said contacts have separated and effectively sealing said nozzle for said second arc chute until said movable blade contact has traveled a predetermined distance.
